UNITED STATES PATENT OFFICE.

STANLEY E. BROWN, OF MIDDLEBURY, VERMONT.

MANURE-REMOVER.

1,388,796.

Specification of Letters Patent. Patented Aug. 23, 1921.

Application filed December 2, 1919. Serial No. 342,008.

To all whom it may concern:

Be it known that I, STANLEY E. BROWN, a citizen of the United States, and a resident of Middlebury, in the county of Addison 5 and State of Vermont, have invented a new and Improved Manure-Remover, of which the following is a description.

The general object of my invention is to provide a carrier adapted to operate in a trench beneath a stable and adapted to carry the manure therefrom outwardly, as well as to provide for automatically scraping the manure from the carrier to direct it into a wagon.

15 The manner in which the above and other objects are attained and the distinguishing features of the invention will clearly appear from the specific description following.

Reference is to be had to the accompanying drawings forming a part of this specification, it being understood that the drawings are merely illustrative of practical examples of the invention.

Figure 1 is a sectional side elevation of a 25 manure remover embodying my invention in one form;

Fig. 2 is an inverted plan view of the carrier and scraper, the other structural features being omitted;

30 Fig. 3 is an enlarged plan view of the rear end of the carrier;

Fig. 4 is a cross section on the line 4—4 of Fig. 3;

Fig. 5 is an enlarged cross section on the 35 line 5—5, Fig. 1;

Fig. 6 is an enlarged fragmentary inverted plan view;

Fig. 7 is an enlarged section on the line 7—7, Fig. 2;

40 Fig. 8 is an end view of the scraper and the guide members therefor, as well as the means for regulating the height of the scraper;

Fig. 9 is a view similar to Fig. 1 but illustrating a modification;

Fig. 10 is an enlarged detail of the tail board provided on the carrier with the construction illustrated in Fig. 9;

Fig. 11 is a view similar to Figs. 1 and 9 50 but illustrating a further modification;

Fig. 12 is a fragmentary view showing a detail of the flexible supporting strip on the carrier and to which the chain thereof is secured.

55 Referring more particularly to Figs. 1 to 8, I provide a trench 11 beneath the stable

partially represented at 10, said trench leading to a ramp 12 extending to a suitable structure 13 having elevated tracks 14 thereon spaced to permit material to drop between the tracks. A flexible carrier 15 is provided of any suitable form having wheels 16 adapted to travel in the trench 11 and on the ramp 12 and tracks 14, said wheels turning on stud axles 17^a on hangers 17. Adjacent hangers 17 may, as shown, be connected by links 18 suitably secured as at 18^a to adjacent hangers.

A scraper 19 is arranged obliquely on the structure 13 between spaced vertical guide 70 members 13^a and at an elevation above the tracks 14 for the carrier 15 to pass beneath the scraper. The front end 20 of the carrier is preferably inclined and supported on a front wheel 16^a at an elevation for the 75 front edge of the end 20 to pass beneath the scraper 19 to slightly raise the latter and insure a scraping engagement of its lower edge with the top surface of the carrier to deflect the manure therefrom laterally permitting it to drop into a wagon (not shown).

On the carrier 15 is a flexible chain rack 21, certain links of which have brackets or lugs 21^a secured to a longitudinal flexible strip 21^b ranging lengthwise of the carrier 85 adjacent to the center thereof so that the chain rack 21 is at the longitudinal center or approximately so. Said rack 21 is engaged by sprocket wheels 22 on transverse shafts 23 which are provided with sprocket 90 pulleys 24 at one end over which a chain 25 runs connecting up the two shafts; one shaft 23 is a driven shaft and is driven from any convenient source of power, there being provided for the purpose in the illustrated 95 example, a worm wheel 26 on the shaft engaged by a worm 28 on a shaft 27, here shown as having a universal joint 29 and extending into the stable 10 where it is provided with pulleys 30 adapted to be driven 100 by any convenient power, such for example, as a gas engine (not shown) with which stables are now usually equipped.

The scraper 19 is provided with vertical rods 31 extending downwardly therefrom 105 through suitable guide members such as lugs 32 on the structure 13 and provided at their lower ends with springs 33, coiled thereabout between the lugs 32 and nuts 34, the springs being adapted to yield to the wedging action of the inclined end 20 of the carrier. Beneath the scraper 19 means is pro-

vided to regulate the height of the lower edge thereof, said means preferably consisting of cams 35, 35^a near each end of the scraper. One cam 35 is rigid with a lever 37 fulcrumed at its lower end as at 36 on a bracket 38 or other support on the structure 13, said lever being provided with a latch 39 adapted to engage an arcuate rack 40. The opposite cam 35^a is rigid with a lever 42 fulcrumed at its lower end as at 41 on the structure 13, said lever 42 being connected by a link 44 with the lever 37 between the ends of the latter as at 43, and the arrangement being such that the scraper 19 resting on the cams 35, 35^a may be raised or lowered with the rocking of the lever 37. A depending scraper 45 is provided on carrier 15 at the rear end to scrape the bottom of trench 11, the scrapings being adapted to be carried through said trench and over the ramp 12 to the structure 13 to drop between the tracks 14 into a wagon or onto the ground. Also, side scrapers 46 are provided on said carrier near each end at the sides to project beyond the side edges for scraping the side walls of trench 11. Short vertical rods or pivots 47 carrying said scrapers 46 extend downwardly through the carrier 15 and are provided with lateral arms 48 to be connected with one end of a retractile spring 49, the opposite end of the spring being secured to fixed pins 50 or the like at the under side of the carrier. In Fig. 9 a carrier 15^a is adapted to run in a trench 11^a beneath the stable 10^a and over a bridge 12^a forming a continuation of said trench, outside the stable, and pivoted as at 57 to swing in a vertical plane for permitting the wagon to be driven beneath the bridge. The arrangement is designed particularly for side-hill land and the bridge 12^a leads to a structure 13^b having fixed tracks 14^a. The carrier 15^a is provided with wheels 16^b and the front end 20^a of said carrier is supported inclined by a small wheel 16^c to wedge itself beneath the scraper 19, which scraper is arranged and equipped as previously described. The supporting rods of the scraper as well as the springs thereon and means for raising and lowering the scraper having been fully described, the description need not be repeated in connection with Fig. 9. The bridge 12^a is raised and lowered by suitable means such as a rope 58 secured to the front end of the bridge as at 58^a and running over a sheave 59 on stable 10^a, the rope in practice extending to any convenient point that it may be grasped and made fast after the bridge has been positioned as desired. The rear end of carrier 15^a is provided with a tail board 46^a hinged at its lower end as at 51 to the rear end of the carrier. A hanger 53 on the tail board at the outside to be swingable therewith, is pivotally connected

at its lower end to a horizontal pin 52 extending forwardly beneath the carrier through a guide bracket 54 said pin having a spring 55 coiled about the same and bearing against said bracket 54 and against collar 56 on the pin, the arrangement being such that as the tail board 46^a strikes the scraper 19, it may turn on its hinge 51, the spring 55 serving to restore the tail board to its vertical position. A haul rope 60 is secured to the front end of the carrier 15^a and may be hitched by any suitable means (not shown) to a draft animal for hauling the carrier. A return rope 60^a is secured as at 60^a to the rear end of the carrier 15^a, 80 and passes over suitable pulleys 60^c, 60^d.

In the form shown in Fig. 11 the carrier 15^b has wheels 16^d adapted to travel in the trench 11^b beneath the stable 10^b and onto a ramp 12^b which is supported between the said trench and the outer structure 13^c, supporting the trackways 14^b and scraper 19. A haul rope 60^a is connected with the front end of the carrier 15^b and is adapted to run along the ramp 12^b and through the structure 13^d 90 to be hitched to a draft animal for the forward haul of the carrier to said structure. A second haul rope 60^b runs over suitable guide pulleys such as a pulley 61 on ramp 12^b, pulleys 61^a on structure 13^b and the pulley 61^b in the trench 11^b near the rear end thereof, said haul rope 60^b being secured at its rear end as at 61^c to the under side of the carrier near the rear end. Said carrier is provided with a rigid end board 46^b at the rear end and has a depending scraper 45. The front end 20^b of carrier 15^b is supported inclined by a low front wheel 16^e.

As seen in Fig. 12 the strip 21^a is formed with kerfs 21^d as one means of producing a 105 flexible strip.

To tighten the chain 21 where it engages the sprocket wheel 22 I employ tighteners at opposite sides of said sprocket wheel and this may consist as shown of standards 65 110 having their upper ends 66 extending laterally over the chain 21 to bear down upon the same. Said standards are secured in the present example to cross bars 67 on the frame 13 by a slot and pin connection, there being slots 68 in said standards and pins or bolts 69 securing the same to bars 67.

I would state in conclusion that while the illustrated examples constitute practical embodiments of my invention, I do not limit myself strictly to the mechanical details herein illustrated, since manifestly the same can be considerably varied without departure from the spirit of the invention as defined in the appended claims.

Having thus described my invention, I claim:

1. An apparatus of the class described including a scraper, a carrier adapted to travel beneath said scraper, and means yieldingly 130

supporting said scraper, the forward end of said carrier presenting a dip to exert a wedging action against the lower edge of the scraper.

- 5 2. An apparatus of the class described including a structure, a runway leading to said structure, a carrier movable along said runway to and from said structure, and adapted to receive material at the top surface thereof, means on said structure adapted to dislodge material from the top of the carrier, and a scraper on said carrier at the underside adapted to scrape the bottom of said runway.
- 10 3. An apparatus of the class described including a structure, tracks thereon spaced

to permit material to drop therebetween, a runway leading to said tracks, a carrier movable on said runway and adapted to receive material at the top surface thereof, a scraper 20 on the carrier at the underside adjacent the rear end to scrape said runway and drag the scraped material to said tracks to permit the material to drop between the tracks, and scraper means on said structure above the 25 tracks beneath which scraper said carrier is adapted to travel for the scraping of the material from the top surface of the carrier, said scraper being adapted to scrape the material laterally from said structure.

STANLEY E. BROWN.
